Primary Examiner — Nathan M Johnston(74) *Attorney, Agent, or Firm* — Leydig, Voit & Mayer, Ltd.(57) **CLAIM**

The ornamental design for a blood flow line, as shown and described.

DESCRIPTION

FIG. 1 is a top, front, left side perspective view of a blood flow line showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The broken lines shown in the drawings illustrate portions of the blood flow line which form no part of the claimed design.

1 Claim, 7 Drawing Sheets(56)
